UNITED STATES PATENT OFFICE.

LOUIS F. WEGENER, OF ST. LOUIS, MISSOURI.

REFRIGERATING MACHINE.

Application filed August 10, 1925. Serial No. 49,463.

This invention relates to a refrigerating machine, and more particularly to means for insuring the efficiency of the compressor, means for automatically draining the oil which is discharged with the gas from the high pressure chamber, and means for utilizing the oil for lubricating the plunger in the compression cylinder.

With the foregoing and other objects in view, the invention consists in the novel construction and arrangement of elements described, illustrated and claimed, it being understood that modifications may be made within the scope of the claims without departing from the spirit of the invention.

In the drawings forming part of this application:

Figure 1 is a view of the machine in vertical section.

Figure 2 is a section on line 2—2 of Figure 1.

Figure 3 is a section on line 3—3 of Figure 1.

The housing 10 provides a low pressure chamber 12, and includes a head or the like comprising the horizontal portion 13, the upwardly extending flange 14 surrounding a central opening or upper chamber, and further includes an outwardly extending flange 15.

An upper casting carried by head 13, or by the upper flange 15 thereof, includes a horizontal flange 16, a vertical body or flange 17 and an upper flange 18 supporting a cover 19. This construction provides a valve chamber 20 and within this chamber is a valve casing 21 having an upper flange 22 resting upon annular rib 23' on body 17. An outlet duct is designated 23 and communicates with the interior of a chamber 25 formed in upper housing element 26, this chamber 25 constituting a high pressure chamber and having an outlet connection 27 leading to a condenser, not shown. Housing 26 has a lower flange 28 which is bolted to the horizontal portion of the head, the latter including a flange 13' through which bolts 29 pass, being secured by nuts 30. An outlet connection for the high pressure chamber 25 is shown at 33.

Within upper chamber 12' which communicates with low pressure chamber 12, I provide a cylinder 35 which has communication through port 36 with said low pressure chamber 12. A piston 37 operates in the cylinder, and gas from low pressure cham-

ber 12 passing through upper chamber 12' and port 36 into the cylinder is compressed by the operation of the piston or plunger and is forced out through a valved opening 60 or port, the construction of the valves being of particular importance.

A disk valve is designated 40 and is provided with an aperture or apertures 41 through which the gas passes after being compressed. The gas flows thence from valve casing 21 to and through duct or discharge pipe 23 to high pressure chamber 25. Disk valve 40 is normally closed under the action of spring 42, and aperture or apertures 41 in the disk valve are normally closed by valve 44 acted upon by the flat spring or resilient element 45 secured at 46 in the body of valve 40. The spring 42 is of greater strength than spring 45, and valve 40 therefore opens only under a predetermined pressure greater than the pressure required to open the smaller valve.

The lubricating and oil sealing portion of the construction constitute an important part 80 of the invention and will now be described. Oil passes into the high pressure chamber 25, incident to the operation of the refrigerating machine, and passes thence through outlet connection 33, pipe 50 to the connection 51 of housing 52. Chamber 53 communicates with a port 54 closed by a needle valve 55, and the stem of this valve carries collars 56 and 57 between which the ends 58 of levers 60 are positioned, these levers 90 being of the form illustrated in Figure 1 and including an upper arm, a downwardly extending arm and an inwardly and laterally extending portion. The levers are pivoted at 61, and their upper ends are pivotally 95 connected at 62 with ears formed on the lower portion of a hollow float 65. This float operates in chamber 66 of housing 52, and the float has a central stem 67 operating in tubular portion 68 depending from the cover 69 of housing 52. An oil connection, comprising a tubular element 70 depends into the chamber formed within the hollow float 65, the upper part of this tubular member having connection with an oil pipe 71 100 passing through the housing 10, through low pressure chamber 12, and being fixed in the wall of cylinder 35 in the manner shown in Figure 1. The position of the discharge end 72 of this oil pipe, with reference to the port 36 on the opposite side of the cylinder wall is 105 important.

110

Oil will drain from the high pressure chamber 25, will pass through pipe 50, chamber 53, port 54, into the main chamber of housing 52, until the chamber is sufficiently filled to cause the oil to flow over the upper edge of the float 65 and into the chamber or reservoir provided in the float. When the weight of the oil within the float is sufficient, the latter will descend to a point 10 where the valve 55 will close port 54, cutting off the inflow of fluid. The suction produced in the cylinder 35, in the operation of the machine, will then result in the flow of oil from the chamber within the float 15 through tubular member 70, pipe 71 and the discharge end 72 thereof into the cylinder, for the purpose of establishing an oil seal for the piston and for lubricating the latter. It should be added that the piston 37 has 20 connection by means of pin 75 with connecting rod 76 operated by the eccentric mechanism shown in Figures 1 and 3. Eccentric straps or bands 77 cooperate with eccentric 25 straps 78 rigidly mounted on shaft 79, the latter operating in bearings 80 and 81 formed on the heads 82 and 83 having the relation to housing 10 illustrated in Figure 3. A stuffing box is designated 84, and serves the usual purpose, this box or outer wall thereof 30 being formed on head 83.

Having thus described the invention, what is claimed as new, is:-

1. In a device of the class described, a chamber including a lower inlet connection 25 and a valve therefor, a stem for the valve, engaging means on the stem, angular pivoted

devices fulcrumed on opposite sides of the stem and having their shorter arms cooperating with the stem for lifting the valve, a vertically movable open top receptacle within the chamber, the long arms of the pivoted devices being pivotally connected with the receptacle at points diametrically opposite their pivotal points, means for guiding the receptacle in its vertical movement, and means extending to a point of discharge, and leading from the receptacle for conducting fluid introduced thereto under pressure thru the valve and thru the chamber.

2. In a device of the class described, a pressure chamber having a lower outlet for the discharge of fluid, a second chamber including a lower inlet connection and a valve therefor, a stem for the valve, engaging means on the stem, angular pivoted devices fulcrumed on opposite sides of the stem and having their shorter arms cooperating with the stem for lifting the valve, a vertically movable open top receptacle within the second chamber, the longer arms of the pivoted devices being pivotally connected with the receptacle at points diametrically opposite their pivotal points, means for guiding the receptacle in its movement, and means extending to a point of discharge from the receptacle, for conducting fluid therefrom under pressure supplied from the chamber first named, thru the valve, and to the receptacle.

In testimony whereof I affix my signature.

LOUIS F. WEGENER.
